PC(57) **CLAIM**

The ornamental design for a display screen with graphical user interface, as shown and described.

DESCRIPTION

FIG. 1 is a front view of a display screen with graphical user interface showing our new design;

FIG. 2 is a partial enlarged view taken along line 2-2 in FIG. 1;

FIG. 3 is a partial enlarged view taken along line 3-3 in FIG. 1;

FIG. 4 is a partial enlarged view taken along line 4-4 in FIG. 1; and,

FIG. 5 is a partial enlarged view taken along line 5-5 in FIG. 1.

The outermost broken line rectangle shows a display screen that forms no part of the claimed design. The remaining broken lines show parts of the graphical user interface that form no part of the claimed design.
